UNITED STATES PATENT OFFICE.

JESSE F. A. AULT, OF CAMBRIDGE, OHIO.

REINFORCED-CONCRETE RAILWAY-TIE.

1,010,399.

Specification of Letters Patent. Patented Nov. 28, 1911.

Original application filed April 27, 1911, Serial No. 623,669. Divided and this application filed August 7, 1911. Serial No. 642,584.

To all whom it may concern.

Be it known that I, JESSE F. A. AULT, a citizen of the United States, residing at Cambridge, in the county of Guernsey and State of Ohio, have invented certain new and useful Improvements in Reinforced-Concrete Railway-Ties; and I do declare the following to be a full, clear, and exact description of the invention, such as will enable others skilled in the art to which it appertains to make and use the same.

This application is a division of my prior application Serial No. 623,669, filed April 27, 1911 and the present invention relates to railway ties and has for its object to provide an improved reinforced concrete railway tie.

With this object in view, the invention consists in the improved construction, arrangement and combination of parts of a tie of this character which will be herein-after fully described and afterward specifically claimed.

In order that the construction and operation of my invention may be readily comprehended, I have illustrated a preferred embodiment thereof in the accompanying drawings in which:

Figure 1 represents a perspective view of my improved tie, parts being broken out to show the reinforcing or bonding rods and carrier in position; Fig. 2 represents a top plan view of the tie on a somewhat reduced scale; Fig. 3 represents a sectional view through the reinforcing rods in operative position showing the bond-carrier in elevation, also in operative position upon the rods; Fig. 4 represents an edge elevation of the parts shown in Fig. 3; Fig. 5 represents a top plan view of the parts shown in Fig. 3.

Like reference characters mark the same parts in all the figures of the drawings.

Referring specifically to the drawings, my improved tie, indicated at 10, is composed of any well known concrete or like mixture reinforced by a number of, preferably four, square twisted rods 11, 12, 13 and 14, preferably located longitudinally in the tie in positions representing the four corners of a square or rectangle and held in such position during the molding of the tie by means of my improved bond-carrier 15, the position of the reinforcing rod and bond-carrier in the tie being clearly illustrated in Figs. 1 and 3 especially.

The bond-carrier 15, when ready for use

in the mold, comprises a base-bar 16, top bar 17, loops 18, 19, 20, 21, for embracing respectively, the reinforcing rods 11, 12, 13 and 14, and upright bars 22 and 23 connecting, respectively, loops 18 and 20 and 19 and 21, the position of the inner portion of the material forming the several loops and the uprights 22 and 23 when placed in position to receive the reinforcing bars, being in a single, or the same plane with the loops turned inward from the ends of the cross bars and the upright bars centrally located and side by side, as indicated in dotted lines in Fig. 3, the main portion of the loops with the base-bar 16 and top bar 17, and the upright bars 22 and 23 in their final position, being indicated in full lines in that figure. With the parts of the bond-carrier in the positions described, the rigidity of the reinforcing rods 11, 12, 13, and 14 would depend upon the fit of the loops upon the bars, but this might be somewhat unreliable, and in order to avoid this uncertainty, after the carriers have been placed in position on the rods with the parts in the dotted line position of Fig. 3, I bend the inner portions of the metal which forms the loops inwardly, out of the plane in which these parts are first located into the positions indicated in Figs. 1, 4, and 5, and in full lines in Fig. 3. In this position the metal forming the loops is much more closely entwined and more rigidly held around the reinforcing rods 11, 12, 13, and 14, and the upper ends of the vertical bars 22 and 23 are brought into position to utilize them for another purpose later described.

With the reinforcing rods and the bond-carrier in position, as described and as shown in Fig. 1, I will have provided a thoroughly strengthened tie, and in order to afford means for the proper reception of the rail plate and rail upon the tie and the proper securing of the same thereon, I have provided transverse notched seats 24 and 25 in the top of the tie, and the location of these seats relative to the reinforcing rods and bond-carriers is such that the uppermost points of the reinforcing rods, as at 26 will be flush with the surface of the tie in the seating notches 24 and 25 and the upper ends 28 of the upright-bars 22 and 23 of the bond carrier will be flush with the same surface.

The upper cross bar 17 of the bond car-

rier is flush with the upper surface of the tie itself and will form the outer wall of each of the notched rail seats 24 and 25, thus affording a much greater resistance to 5 lateral outward spread of the rails secured in said notched seats. In order to accommodate these upper cross bars 17 of the bond-carrier, the outer wall of each notched seat is recessed at 29, as clearly shown in Figs. 10-1 and 2, so as to bring the metal of the upper bars 17 into direct contact with the outer edge of the base of the rail plate to prevent the crumbling or gradual wearing 15 away of the outer walls of the notched seats.

15. The bottom of the rail plate will thus be seated directly upon the upper surface of the longitudinal reinforcing rods 11, 12, 13, and 14, and upon the upper ends of the bars 20 22 and 23 of the bond-carriers, which will also prevent to a very large extent, the wearing away of the surface of the concrete tie.

25. The utility and superiority of my improved tie as just described will be obvious and it will be clearly evident to those skilled in the art that the quality of the mixture of which the tie is made, the size and material of the various metal parts used, and their relative shapes and locations, may be considerably varied without departing from the spirit and scope of the invention.

o I claim as my invention:

1. A bond-carrier for a molded railway tie comprising transverse upper and lower 5 cross bars, loops at the outer ends of each of said cross bars turned inwardly toward the center thereof, and parallel upright bars connecting the inner ends of the loops of the respective cross bars, the upright bars being centrally located with relation to the cross bars and all of the parts being in a single plane.

o 0 2. A molded railway tie having reinforce-

ing elements comprising bond-carriers, each 4 consisting of parallel upright bars and outwardly extended loops at each end of each bar, the upper loops being connected by an upper cross-bar and the lower loops by a lower cross bar, and longitudinal reinforcing rods secured in the loops by forcing the 5 upright bars out of the plane of the base and top bars, and thus closing the loops very effectually about the longitudinal bars.

3. A molded railway tie provided with 5 transverse notched rail seats, longitudinal reinforcing rods embedded in the tie flush with the bearing surface of said seat, and bond-carriers embracing said rods having upright bars, the upper ends of which are also flush with the bearing surface of said 6 seats.

4. A molded railway tie provided with 6 transverse notched rail seats, longitudinal reinforcing rods embedded in the tie flush with the bearing surface of said seats, bond-carriers embracing said rods and having top bars projecting above the longitudinal rods and forming outer walls for the rail seats.

5. A molded railway tie provided with 7 transverse notched rail seats, longitudinal 7 reinforcing rods embedded in the tie flush with the bearing surface of said seats, and bond-carriers embracing said rods having upright bars, the upper ends of which are also flush with the bearing surface of said 7 seats, and top bars projecting above the longitudinal rods and forming outer walls for the rail seats.

6 In testimony whereof I have hereunto set my hand in presence of two subscribing witnesses.

JESSE F. A. AULT.
